CENTRIFUGAL CASTING MACHINE

Application filed May 28, 1928. Serial No. 281,323.

This invention relates to new and useful improvements in centrifugal casting machines adapted for use in dental laboratories, in the art of preparing inlays, crowns, and 5 other dental work.

Centrifugal casting machines, now commonly employed in dental laboratories, usually require that the gold or metal to be cast, be plated in an open crucible supported 10 in the machine, and heated with a blow torch until it is melted to the proper consistency, after which the casting machine is manually started and the molten gold or metal is delivered, by centrifugal force, into 15 a mold positioned adjacent to the crucible. This method of heating or melting the metal has proven unsatisfactory because no means are provided for indicating to the person who is operating the machine, the temperature 20 of the metal before the machine is started and, consequently, the gold or metal is not always heated to the same temperature before it is delivered into the mold to be cast.

25 It is now common practice for the person who is melting the gold, to observe it carefully as it is being heated, and when it "appears" melted or heated to the right temperature for casting, the machine is started, 30 and the molten metal is delivered into the mold by centrifugal force. If the gold or metal has not been sufficiently heated or melted before the machine is started, the molten metal may not enter the usual small 35 sprue hole provided in the flask. Conversely, if the metal is overheated, it will "burn" the gold or metal, which will result in the production of a poor casting and in some cases, the metal cannot be cast at all. If it 40 does flow into the flask, when thus burned, the resultant casting will usually be very rough. Also, if the gold has been overheated or "burned", during the melting process, it will not produce a homogeneous 45 casting or article, and consequently, the resultant article will not be of the highest standard.

It is an object of the present invention to 50 provide a dental casting machine provided with means for automatically starting the

rotation of the machine, when the gold or metal has been heated to a predetermined temperature, thus eliminating all guess work from the operation of preparing dental castings.

A further object is to provide a centrifugal casting machine which will be entirely automatic in operation, from the standpoint of heating and melting the metal and starting the machine, subsequent to placing the 55 gold or metal within the heating chamber thereof.

A further object is to provide a centrifugal casting machine comprising a supporting bar mounted for rotary movement, in 60 substantially a horizontal plane and normally retained in inoperative position, and the member having an electrically operated heating chamber mounted thereon adapted to receive the metal to be cast, and means being associated with said heating chamber and responsive to temperature changes within the heating chamber, to automatically release said bar from its retaining means, after 65 a predetermined time interval, whereupon 70 the bar will start to rotate, causing the molten metal within the heating chamber to be delivered into a suitable mold or flask, positioned adjacent one end thereof.

A further object of the invention is to so 75 provide a centrifugal casting machine comprising a base member having a bar mounted for rotation in the upper portion thereof, but normally retained in inoperative position by a retaining member mounted in the 80 base, an electrically operated heating chamber adjustably mounted upon the bar and having a circuit connected with a source of supply, a solenoid coil mounted upon the 85 base and having an armature associated with the bar-retaining member and having a circuit associated with the heating circuit and normally open, and a thermo-element being mounted within the heating chamber and functioning to close the solenoid circuit, 90 after a predetermined time interval, whereupon the armature will be actuated to move the bar-retaining member out of locking engagement with the bar to permit rotation of 95 the bar and heating chamber.

A further object is to provide a dental casting machine of the centrifugal type, comprising a base having a suitable motor mounted therein for operating a bar 5 mounted in the upper portion of the base and adapted for rotary movement in substantially a horizontal plane, and a heating chamber being mounted upon the bar adjacent to a mold support adapted to 10 mountably receive a mold or flask, which, when mounted upon the support, will have its interior or cavity communicating with the heating chamber through a small sprue hole, and the bar normally being held in 15 inoperative position by means of a retaining member operatively connected with a solenoid having a circuit electrically connected with the heating circuit for the heating chamber, and a thermo-element being associated with the heating chamber and responsive to temperature changes within the chamber, to effect the closing of the solenoid circuit, whereupon the solenoid will move the bar-retaining member out of engagement 20 with the bar to permit the latter to rotate, and the actuation of said retaining member also automatically opening the solenoid and heating circuits, which circuits will thereafter remain open until the bar is again 25 locked against rotation by moving the retaining member into engagement therewith.

A further object is to provide an electrically controlled dental casting machine comprising an electrically heated chamber 35 adapted to receive the metal to be cast, and to melt the latter to the desired degree for casting, the heating chamber being mounted upon a rotary bar which normally is locked against rotation by a locking member, and 40 when said locking member is in bar-locking position, the heating circuit and also a solenoid circuit will be conditioned for operation, and when current is supplied to the heating circuit, the chamber will be heated 45 to melt the metal therein, and the rising temperature in the heating chamber will effect a thermo-element, electrically connected with the heating and solenoid circuits, which will cause the closing of the 50 solenoid circuit, after a predetermined time interval, whereupon the locking member will be actuated to release the bar and permit it to rotate, movement of the locking member 55 also causing the heating and solenoid circuits to be opened.

The particular object of the invention, therefore, is to provide a centrifugal casting machine having means for electrically heating the gold to a predetermined temperature, 60 whereupon the machine will be automatically started and the circuit to the heating coil opened, thus assuring that each casting will be of the same consistency because the metal or gold nugget will be heated to the proper temperature to produce a perfect 65

casting, before the machine is initially started.

Other objects of the invention will appear from the following description and accompanying drawings and will be pointed out 70 in the annexed claims.

In the accompanying drawings, there has been disclosed a structure designed to carry out the various objects of the invention, but it is to be understood that the invention is 75 not confined to the exact features shown as various changes may be made within the scope of the claims which follow.

In the accompanying drawings forming part of this specification;

Figure 1 is a diagrammatic sectional view illustrating the invention as applied to a dental casting machine, the thermo-element being shown in circuit-opening position;

Figure 2 is a detail sectional view of the 85 heating chamber, showing the thermo-element in circuit-closing position; and

Figure 3 is a wiring diagram.

In the selected embodiment of the invention here shown, for purposes of disclosure, 90 there is illustrated a dental casting machine of the centrifugal type, comprising a housing 2 having a suitable flange 3 at the bottom thereof to provide means for securing it to a suitable support 4, by such means as 95 screws 5. A shaft 6 is rotatably mounted in a cap 7, suitably secured to the upper portion of the housing 2, and has its lower end operatively connected with a suitable spring 100 motor 8, of ordinary construction. A bar 9 is secured to the upper end of the shaft 6 and is adapted for rotation in substantially a horizontal plane. A suitable ratchet device 10 is provided to permit the bar 9 to over-run, or continue rotating after the 105 spring motor 8 has spent its energy.

The means provided for heating the metal or gold to be cast is shown at the left hand side of Figure 1, and comprises a heating chamber 11, surrounded by a heating coil 12 having conductors 13 and 14 leading to suitable contact fingers 15 and 16, respectively, mounted in an insulating block 17 secured to the bar 9.

A mold support 18 is adjustably mounted 115 upon one end of the bar 9 adjacent to the heating chamber 11 by means of a suitable adjusting screw 19, received in a slot 21 provided in the bar. The heating chamber 11 and coil 12 are mounted within a suitable 120 casing 22 which preferably is adjustably secured to the bar 9 so that the mold support and heating chamber may be relatively adjusted with respect to one another, to accommodate the machine for various sizes of 125 molds. In the drawings, there is shown a mold 23, of ordinary construction, positioned upon the mold support at the outer end of the heating chamber. This mold is 130 filled with the usual investment material 24

and has a cavity 25 therein connected with the heating chamber 11 by means of the usual sprue hole 26. A weight 27 is adjustably secured to the opposite end of the bar 9 by a suitable adjusting screw 28. This weight functions to counterbalance the mechanism mounted at the opposite end of the bar so that the machine will operate without vibration, when the bar 9 is released, during the casting operation.

The contact fingers 15 and 16 are adapted to engage contacts 29 and 31, electrically connected with wires 32 and 33, respectively, which have contacts 34 and 35, respectively, connected therewith. These contacts are adapted to engage contact clips 36 and 37 electrically connected with the main line conductors 38 and 39. A switch 41 provides means for opening and closing the supply circuit to the apparatus.

The means provided for normally retaining the bar 9 in inoperative position, when the spring motor 8 is wound up, consists of a rod 42 slidably mounted in suitable guides 43 and 44, provided respectively in the cover 7 and housing 2, as shown in Figure 1. This rod 42 functions to arrest movement of the bar 9, prior to starting the casting operation. An insulating block 45 is secured to the upper end of the rod 42 and provides a support for the contacts 29 and 31, previously described. A third contact 46 is also mounted in the insulating block 45 and has a wire 47 connecting it with one end of a solenoid 48, here shown as being within the housing 2. The other side of the coil 48 has a wire 49 connecting it with the wire 33, shown in Figures 1 and 3.

40 An armature 51 is movably mounted within the solenoid coil 48 and has a recessed portion 52 adapted to receive one end of a lever 53, mounted upon a fixed pivot pin 54. This lever has its opposite end pivotally connected to the lower end of the rod 42 by a pin 55, and has an end portion 56 projecting through a slot 57 in the housing, whereby it may be manually operated to move the rod 42 into locking engagement with the bar 9. Energization of the solenoid coil 48 will effect the automatic release of the bar 9, because of the upward movement of the armature 51 which will cause the shoulder 58 of the armature to engage the terminal of the lever 53, resulting in the opposite end of the lever being moved downwardly with the resultant downward movement of the rod 42, and therefore the release of the bar 9. The armature is normally supported upon a suitable support 59.

60 An important feature of this invention resides in the means provided for automatically closing the solenoid circuit, after a predetermined time interval, subsequent to the placing of the metal or gold within the heating chamber 11. Such means comprises a
65

thermo-element 60, preferably mounted within the heating chamber 11 and having one end fixed to the heating coil supporting means, as shown in Figure 1, and having a wire 61 connecting it with a contact finger 62 mounted in the insulating block 17. The finger 62 is adapted to engage the contact 46. The opposite or movable end of the thermo-element 60 is mounted in a guide 63, of insulating material, and is adapted to engage a contact screw 64 adjustably mounted in a small bracket 65, having a wire 66 connecting it with the wire 13 of the heating coil. 70 75

To start the casting operation, the spring motor 8 is wound up by manually rotating the bar 9, after which the locking member or rod 42 is moved upwardly from the position shown in Figure 2, to that shown in Figure 1, by means of the end portion 56 of the lever 53. Such upward movement of the rod 42 will also move the contacts 46, 29, and 31 into electrical engagement with the contact fingers 62, 15, and 16, respectively, thereby conditioning the heating and solenoid circuits for starting. When the heating chamber is cold, the thermo-element will be contracted as shown in Figure 1, thereby leaving a gap between the movable terminal thereof and the contact screw 64. When the parts have been thus positioned, the metal or gold to be cast, indicated by the numeral 67 in Figure 1, is placed in the heating chamber 11, after which the main switch 41 is moved into circuit-closing position, thereby causing current to flow through the heating coil 12. The heating circuit is

the heating coil 12. The heating circuit is as follows; from the main line wire 38 through the switch contacts 36-34, wire 32, contact 29, finger 15, conductor 13, heating coil 12, conductor 14, contacts 16-31, wire 33, contacts 35-37, and back to the main line wire 39. Functioning of the heating coil will cause the temperature in the heating chamber to rise, thereby causing the thermo-element 60 to elongate and subsequently electrically engage the terminal of the contact screw 64. Such engagement of the thermo-element with the screw 64 will effect the closing of the solenoid coil 48, whereby the armature 51 will be drawn upwardly, causing the shoulder 58 to strike the end of the lever 53 and move it upwardly into the dotted line position shown in Figure 1. Such movement of the lever 53 will cause the rod 42 to be moved downwardly to the position shown in Figure 2, causing the upper end thereof to be moved out of locking engagement with the bar 9, and, at the same time, moving the contacts 46, 29, and 31 out of electrical connection with the contact fingers 62, 15, and 16, respectively, as shown in Figure 1, and thereby causing the heating and solenoid coils to cease to function. Movement of the rod 42 out of engagement with the bar 9 will permit the motor to

rotate the bar, thereby causing the molten metal 67 to be delivered into the cavity 25 by the centrifugal action of the rapidly rotating bar 9. The bar will continue to rotate until the motor has spent its energy.

5 It will therefore be seen that this novel casting machine is adapted for automatic operation, after the gold has initially been placed in the heating chamber 11, and the starting switch 41 is closed. Because of the 10 contacts 46—29—31 being moved out of electrical connection with their respective contact fingers 62—15—16, the instant the bar 9 is released, no current will be consumed 15 during the period of rotation of the bar, nor while the machine is at rest, thereby providing a very economical machine. The metal may be heated or melted to the required temperature by adjustment of the 20 contact screw 64.

In the drawings, I have shown this novel gold-melting and casting mechanism as applied to an ordinary centrifugal machine, but it is to be understood that it may be 25 used in connection with various forms of dental casting machines without departing from the scope of the invention.

I claim as my invention:

1. A centrifugal casting machine provided 30 with a heating chamber adapted to receive the metal to be cast, a heating circuit for said chamber, a switch for closing said circuit to effect heating of said chamber, and means within said chamber responsive to 35 temperature changes and adapted to effect opening of said heating circuit, after a predetermined time interval.

2. A centrifugal casting machine provided 40 with a rotary heating chamber adapted to receive the metal to be cast, a heating circuit for said chamber, a switch for closing said circuit to effect heating of the chamber, and means in said chamber responsive to 45 temperature changes and adapted to effect opening of said heating circuit and simultaneously to start rotation of the heating chamber.

3. A centrifugal casting machine provided 50 with a rotary heating chamber adapted to receive the metal to be cast, a heating circuit for said chamber, locking means normally preventing rotation of said chamber, a solenoid circuit operatively associated with said locking means and said heating circuit, and a 55 thermo-element in said heating chamber responsive to temperature changes and adapted to effect energization of the solenoid, whereby said locking means will be actuated to permit rotation of said heating chamber.

60 4. A centrifugal casting machine provided with a rotary heating chamber adapted to receive the metal to be cast, a heating circuit for said chamber, locking means normally preventing rotation of said chamber, 65 a solenoid having a circuit operatively asso-

ciated with said locking means and said heating circuit, and a thermo-element in said heating chamber responsive to temperature changes and adapted to effect energization of the solenoid upon a predetermined temperature in said chamber, whereby said locking means will be actuated to permit rotation of said heating chamber, actuation of said locking means also causing said heating and solenoid circuits to be opened.

5. A centrifugal casting machine provided with a rotary heating chamber adapted to receive the metal to be cast, a heating circuit for said chamber, locking means normally preventing rotation of said chamber, a solenoid having a circuit operatively associated with said locking means and said heating circuit, a thermo-element positioned adjacent a wall of said heating chamber and responsive to temperature changes in the 85 chamber and adapted to close said solenoid circuit upon a predetermined temperature, whereby said locking means is actuated to permit rotation of said heating chamber, actuation of said locking means also causing 90 said heating and solenoid circuits to be opened.

6. A centrifugal casting machine comprising a rotatable bar, a driving means therefor, means for arresting movement of said bar, a mold demountably secured to said bar, casing also secured to said bar and having heating chamber therein, a heating circuit for said chamber, a thermo-element associated with the chamber and responsive to 95 temperature changes therein to effect actuation of said locking means and whereby said bar is released and simultaneously said heating circuit is opened.

7. A centrifugal casting machine comprising 105 a rotatable bar, a motor connected therewith and constantly tending to rotate the bar, means for locking the bar against rotation, a mold and a casing adjustably secured to the bar, said casing having a heating chamber 110 therein, a mechanism adapted to release said locking means, including a solenoid and circuit therefor, a thermo-element connected in series with said solenoid circuit and responsive to temperature changes in the heating chamber, and to cause actuation of said lock-releasing mechanism and to effect the release of said bar.

8. A centrifugal casting machine comprising 120 a rotatable bar, a driving means therefor, means for arresting movement of said bar, a mold demountably secured to said bar, and having an electric heating chamber in communication therewith, a normally open electric circuit associated with said arresting means, a contact in said circuit, and a thermo-element also in the circuit and responsive to temperature changes in said heating chamber whereby, when the temperature therein reaches a predetermined degree, said 130

thermo-element will engage said contact and close said circuit and cause said locking means to be operated to release said bar.

9. A centrifugal casting machine comprising a rotatable bar, a motor connected therewith, a locking member normally positioned in the path of said bar to prevent rotation thereof, a mold and a casing secured to the bar, said casing having an electric heating chamber therein communicating with said mold, an electrically operated device associated with said locking member and adapted to release the latter, a circuit for said device, a contact at one end of the heating chamber electrically connected with said device circuit, and a thermo-bar mounted in the chamber and connected with said device circuit and adapted to engage said contact, upon heating of said chamber, whereby said device circuit will be closed and said electric device operated to move said locking member out of engagement with said bar, to permit rotation thereof.

In witness whereof, I have hereunto set my hand this twenty second day of May, 1928.

LAURITZ B. ANDRESEN.
